UNITED STATES PATENT OFFICE

169,160

PORCH TRELLIS OR SIMILAR ARTICLE

Ernest Meierjohan, Cincinnati, Ohio

Application November 1, 1951, Serial No. 17,213

Term of patent 14 years

(Cl. D54—2)

To all whom it may concern:

Be it known that I, Ernest Meierjohan, a citizen of the United States, residing at Cincinnati, in the county of Hamilton and State of Ohio, have invented a new, original, and ornamental Design for a Porch Trellis or Similar Article, of which the following is a specification, reference being had to the accompanying drawings, forming part thereof.

Fig. 1 is a front plan view of a porch trellis or similar article, showing my new design, the intermediate portion being broken away to indicate indefinite length.

Fig. 2 is a transverse sectional view taken along the lines 2—2 of Fig. 1.

I claim:

The ornamental design for a porch trellis or similar article, as shown and described.

ERNEST MEIERJOHAN.
